UNITED STATES PATENT OFFICE.

FOSTER MILLIKEN, OF NEW YORK, N. Y.

DESIGN FOR A METALLIC POST.

SPECIFICATION forming part of Design No. 21,075, dated September 29, 1891.

Application filed April 25, 1891. Serial No. 390,513. Term of patent 14 years.

To all whom it may concern:

Be it known that I, FOSTER MILLIKEN, a citizen of the United States, residing at New York city, in the county and State of New York, have invented and produced a new and original Design for Metallic Posts, of which the following is a specification, reference being had to the accompanying drawing, forming part thereof, which represents an isometric perspective of a post embodying my design.

The design of the post in plan view consists of two rectangular figures A and B, which figures are oppositely disposed, and the inner or opposed portions of the figures A and B are

carried at a right angle outward, forming flange-like figures b, while between these flange-like figures cylindrical figures a and a' are located. The rectangular figures are further decorated with flange-like side figures d, oppositely located to the figures b.

I claim—

The design for a metallic post, substantially as herein shown and described.

FOSTER MILLIKEN.
